UNITED STATES PATENT OFFICE

DONALD J. MOSSHART, OF LANSDOWNE, PENNSYLVANIA, ASSIGNOR TO WESTINGHOUSE ELECTRIC & MANUFACTURING COMPANY, A CORPORATION OF PENNSYLVANIA

COMBUSTION APPARATUS

Application filed September 14, 1929. Serial No. 392,578.

My invention relates to combustion apparatus and more particularly to progressive feed stokers which include as a part thereof overfeed grate sections of the type comprising a series of grate members disposed in end-to-end relation and extending in the direction of fuel feed; the present invention being an improvement on the invention disclosed and claimed in the copending application of Robert A. Foresman, Serial No. 337,445, filed February 4, 1929, and assigned to the Westinghouse Electric & Manufacturing Company.

As is known, in the downwardly-inclined multiple retort underfeed stoker, the green coal is fed into the ends of the several retorts by main rams, and downwardly through the retorts and upwardly and laterally onto the tuyère rows by secondary rams. As the green coal nears the incandescent fuel bed it becomes heated and the volatiles are driven off. The volatiles combine with the air emitted from the tuyère rows to produce combustion. The remaining solids move laterally on the tuyère rows and the solid carbon content is burned out. The resulting molten ash trickles downwardly through the fuel bed and solidifies as it comes into contact with the upwardly-moving air stream from the tuyère rows. The ash is moved downwardly of the stoker and to the ash disposal apparatus by virtue of its frictional contact with the downwardly-moving fuel bed. This type of stoker is considered the best for coals containing volatiles, for the reason that the air supply in ample quantities is directly adjacent the point where the volatiles are driven off.

From the above description, it may be concluded that the multiple retort underfeed stoker burns coal in lanes. Lanes of green coal are in and over the retort and lanes of burning solid carbons are on the tuyère rows. As the green coal changes to solid carbons it is fed laterally onto the tuyère rows. To the eye of the observer, the lanes are quite perceptible. The lanes in and over the retorts appear relatively dark, due to the presence of volatile matter and the lanes over the tuyère rows appear light.

It is necessary that the air pass uniformly through the tuyère rows in order to obtain efficient combustion, and in order to insure this the movement of the fuel bed must be continuous and uniform so that the ash may be carried away as it forms. 55

Should the ash accumulate at any one point, the flow of air will be restricted at that point and clinkers will result which will interfere with the downward movement of the fuel bed and result in considerable trouble to the operator. In the copending application of Robert A. Foresman, referred to above, a new and improved form of overfeed grate section is disclosed and claimed which receives the burning material as it comes from the underfeed section, positively carries the burning material and ash away from the underfeed section so as to maintain the constant downward movement of the fuel bed 60 and agitates the burning material, thereby breaking down the lanes and permitting air to penetrate and burn out the combustible. 65

As the output of any particular multiple retort stoker is increased, calling for an increased coal feeding rate, more and more coal is burned and as a result more and more ash is deposited on the tuyère rows and has to be carried down by the moving fuel bed. Also, as the length of the underfeed section is increased, the amount of ash to be moved also increases. Obviously, a point will be reached where either the increased output of any particular underfeed stoker or the increased length of the underfeed stoker will result 70 in the accumulation of ash in such amounts that efficient combustion cannot be maintained. 75

In the copending application of Foresman referred to above, it is stated that the secondary rams can be adjusted to push excess coal out of the ends of the retort and this coal can be burned on the overfeed grate section disclosed. That is true, and the green coal discharged from the ends of the retort 80 can be taken care of to a certain extent; but the agitation of this grate will result in the breaking down of the lanes. Obviously, the coal can be fed out of the ends of the retorts 85 in such quantities that an overfeed grate 90

95

in such quantities that an overfeed grate 100

of the Foresman type would break up the lanes before the volatiles of the coal are distilled and the green coal would spread over the grate and seriously interfere with the passage of air through the grate and therefore seriously affect combustion. Air will pass through a fuel bed composed of solid carbons and ash by reason of its porous condition; but the fuel bed composed of green coal is of such a dense character as to seriously interfere with the passage of air therethrough.

The demand for larger and longer stokers is steadily increasing. The underfeed section cannot be built any longer than it is at present for the reason that it will not effectively rid itself of the ash. The length of the overfeed extension grates heretofore known to me are also limited by reason of their construction and operation.

It is, therefore, an object of this invention to provide a progressive feed stoker which can be constructed of any suitable length, and which will at the same time maintain the desired lane burning in an extremely effective manner, will provide for the positive movement of the ash and lastly will break down the lanes at the proper point so that the combustible may be effectively burned out before reaching the ash disposal apparatus.

Another object of this invention is to produce an overfeed grate section which is of improved construction and which operates in an improved manner.

A still further object is to provide an overfeed grate section of the undulatory type and also to provide an improved means for operating the grate section which operation can be varied to suit the burning characteristics of different types of fuel.

These and other objects are effected by my invention, as will be apparent from the following description and claims taken in connection with the accompanying drawings, and forming a part of this application, in which:

Fig. 1 is a plan view of my improved progressive feed stoker;

Fig. 2 is a longitudinal sectional view of the stoker taken on line line II—II of Fig. 1;

Fig. 3 is a transverse sectional view taken on the line III—III of Fig. 2 and illustrating the construction of certain of the grate members of the overfeed grate section;

Fig. 4 is a transverse sectional view taken on the line IV—IV of Fig. 2; and,

Fig. 5 is a sectional view taken on the line V—V of Fig. 2 and illustrating the means for operating the overfeed grate section.

According to the preferred embodiment of my invention which is shown on the accompanying drawings, I provide an underfeed stoker section of alternately-arranged retorts and tuyère rows and having main rams for feeding fuel to the retorts and secondary rams for feeding fuel longitudinally

of the retorts and also upwardly and laterally onto the tuyère rows. I also provide an overfeed grate section disposed transversely of the lower end of the underfeed section which comprises at least one series of grate members pivotally connected together in end-to-end relation and extending in the general direction of the fuel feed. At least the first grate member of the series is supported for straight reciprocatory motion in the direction of the fuel feed so that the lanes of green coal and burning material may retain their proper relation and the ash will be positively moved away from the end of the underfeed section. The number and length of the grate members which reciprocate only, may be varied for stokers of different lengths, i. e., a longer stoker will have a longer straight reciprocating grate surface and a shorter stoker a shorter surface.

The remaining grate members of the series are supported for both bodily movement in the direction of the fuel feed and angular movement about axes extending transversely of the fuel feed. The bodily movement provides for a continuation of the positive progression of the ash and burning material, and the angular movement provides for the breaking down of the lanes and the agitation of the fuel bed so as to permit the air to penetrate and burn out the remaining combustible.

Referring now in detail to the construction illustrated and particularly to Figs. 1 and 2, it will be observed that I have shown a furnace 10, in which a stoker structure 11 is disposed and divides the furnace into a combustion chamber 12 and an air chamber 13. Air is supplied to the chamber by a suitable conduit 14. The stoker structure comprises an underfeed section 15 and an overfeed section 16. The underfeed section comprises a plurality of retorts 17 and tuyère rows 18 arranged alternately with respect to the retorts. The overfeed grate section comprises a plurality of series of grate members 19. The grate members of each series 19 are indicated by the reference numerals 20, 21, 22, 23, 24, 25 and 26 and are pivotally connected together in end-to-end relation by means of suitable pins 27.

The underfeed section is supported at its upper end by a transverse I-beam 28, and at its lower end by pillars 29, which latter are in turn supported by a second I-beam 30. The overfeed grate section 16 is supported at its upper end by the lower end of the underfeed section and at its lower end by a front wall 31 of a clinker pit 32. The intermediate portions of the overfeed grate are supported by supporting structure and its operating means, which are both in turn supported from spaced beams 33. The beams 33 are carried at their upper ends by the

I-beam 30 and at their lower ends by a third transverse I-beam 34.

In operation, coal is fed from a conventional hopper 35 and into the end of each of the retorts 17 by means of a primary ram 36. The coal is fed along the retorts and up over the sides thereof and onto the tuyère rows 18 by means of secondary rams 37, each of which is driven from the primary ram 36 by a rod 38 and lost motion connection 39.

As stated, the overfeed grate section 16 receives the burning material from the underfeed section. The upper portion of the overfeed section is so constructed and operates in such a manner as to carry out the lane burning action commenced on the underfeed section. The first grate member 20 of each of the series is mounted for straight reciprocatory motion. Each of these grate members comprises a grate frame 40 which is rectangular in shape and a plurality of grate bars 41 which are detachably secured within the grate frame 40.

The sides of the grate frames 40 are provided with downwardly-extending lugs 42. (See also Fig. 3.) Pins 43 extend through opening 44 provided in the lower ends of the lugs 42, and supporting rollers 45 are secured to the outer ends of these pins. The rollers are mounted for movement within guideways 46 which latter are secured to spaced angle members 47 extending from the underfeed section.

The grate members 21 of each series comprise grate frames 50, and grate bars 51 detachably secured within the frames. The rear ends of the frames are provided with spaced downwardly-extending lugs 52, which latter are pivotally connected to the upper end of operating links 53. The lower ends of the links are pivotally connected to a rod 54 extending transversely beneath the stoker and supported by the outer ends of lever arms 55. The inner ends of the lever arms 55 are keyed to an oscillating shaft 56 which extends transversely of the stoker and is journaled in suitable supporting standards 57 carried by the beams 33 (see Figs. 1, 2, 3, 4 and 5).

Oscillatory motion is imparted to the shaft 56 by means of a lever arm 58 which is keyed at its upper end to the shaft 56 and pivotally connected at its outer end to the one end of a connecting rod 59. The other end of the connecting rod is pivotally connected by a pin 60 to a lever arm 61, which latter is keyed at its upper end to an oscillating power shaft 62. The power shaft is supported for oscillatory motion by bearings 63 mounted on supporting standards 64 which are carried by the beams 33. (See also Fig. 4.)

The grate members 22 also comprise rectangular grate frames 65 and grate bars 66

detachably secured within the frame. The sides of the grate frames 65 are provided at their rear ends with extensions 67, the under surface of which is formed flat and rests upon rocker-like supports 68. The rocker-like supports are pivotally supported by shafts 69 which extend transversely underneath the overfeed grate and are carried by the upper ends of the supporting standards 57. The rocker-like supports permit the grate member 22 to move both in the direction of fuel feed and angularly about axes extending transversely of the feed.

The grate members 23 of each series comprise grate frames 70 and grate bars 71 detachably secured within the frames, and these grate frames are supported merely at their ends by their pivotal connections with the grate members 22 and grate members 24, respectively.

The grate members 24 comprise grate frames 72 and grate bars 73 detachably secured within the frames. The sides of the grate frames 72 are provided with downward extensions 74, and the lower ends of these extensions are keyed to the power shaft 62.

The grate members 25 comprise grate frames 75 and grate bars 76 detachably secured within the frames, and the rear ends of the side members of the grate frames 75 are provided with rearwardly and downwardly-extending lugs 77, which latter are pivotally connected to the upper ends of floating supporting links 78. The lower ends of the floating supporting links are pivotally supported by a rod 79 extending transversely of the stoker and supported by bearings 80 which latter are carried by the I-beam 34.

The last grate member of each series comprises a grate frame 81 and grate bars 82 detachably secured within the frame. The grate is slidably supported at its rear end by the upper surface of an air and water supply casting 83, which latter is supported by the front wall 31 of the clinker pit.

The grate bars 20, 21, 22, 23, 24, 25 and 26 are each provided along their lateral faces with vertical grooves 84, which provide for the passage of air from the air chamber 13 to the fuel bed supported by the overfeed grate section.

The power shaft 62 is oscillated by means of a lever arm 85 which is keyed to the shaft 62 and operatively connected at its outer end to a connecting rod arrangement 86. The connecting rod arrangement extends outwardly of the furnace and is driven from a suitable electric motor 87.

Oscillatory movement of the power shaft will result in a tilting motion of the grate members 24, about an axis which is transverse to the direction of fuel feed. By reason of the nature of the motion imparted to the grate members 24 and by reason of the piv-

total connections between all of the grate members, the remaining grate members will be moved bodily in the direction of the fuel feed and the grate members 23 and 25 will also move about axes extending transversely of the fuel feed. The floating supporting links 78 will permit the grate members 26 to also move angularly with respect to the fuel-supporting surface.

10 By reason of the lever arm 61, connecting rod 59, lever arm 58, shaft 56, arms 55 and links 53, oscillatory motion of the power shaft 62 will also result in an angular movement of the grate members 21 and 22. The 15 degree of angular movement imparted to the grate members 21 and 22 may be varied with respect to the degree imparted to the grate members 23, 24, 25 and 26. As shown, the lever arm 61 is provided with a plurality of 20 openings 90. The connecting rod 59 may be connected to the lever arm 61 at any one of a number of points by inserting the pin 60 within any desired one of the openings 90, thereby obtaining any desired length of effective lever arm.

15 The operation of my improved progressive feed stoker will be apparent from the foregoing description. The green coal is fed from the hopper 35 and into the upper ends 30 of the retorts 17 by means of the primary rams 36. This coal is forced longitudinally of the retorts and upwardly and laterally over the sides thereof and onto the tuyère rows 18 by means of the secondary rams 37. 35 As stated, the volatiles are largely liberated from the coal while it is within the retort and such volatiles rise upwardly and combine with the air emitted from the adjacent tuyère rows to produce combustion. The solid carbons are forced onto the tuyère rows where 40 they combine with the air emitting therefrom to produce combustion. As stated, this operation can be referred to as lane burning, lanes of green coal within the retort and 45 lanes of solid carbon on the tuyère rows.

50 The green coal is fed into the ends of the retorts in excess of that which can be burned on the underfeed section. The excess green coal is forced out of the ends of the retorts and onto the overfeed grate section. By reason of the straight reciprocatory motion of the upper portion of the overfeed grate section, these lanes are fed downwardly in the direction of fuel feed without disturbing materially their formation. The lane burning commenced on the underfeed section is therefore carried out on the upper portion of the overfeed section. As the coal feeds downwardly from the ends of the retorts, the volatiles will be driven off and these volatiles will combine with air emitting from the adjacent portions of the overfeed grate section. The resulting solid carbons will spill laterally from the coal lanes onto the adjacent por-

tions of the overfeed grate section and there be burned in the same manner as on the tuyère rows. Air cannot pass through that portion of the overfeed grate section which supports the lanes of green coal due to the dense character of such coal; but, the air can pass freely through that portion of the overfeed section which supports the solid carbons and ash, this latter being due to the porous condition of that portion of the fuel bed.

70 It will therefore be seen that the upper portion of the overfeed grate section provides for the same method of burning that is carried out on the underfeed section, and at the same time the reciprocatory motion also provides for the positive and continuous movement of the ash from the tuyère rows. Also, as the lengths of that portion of the overfeed grate section which provides this continuation of the lane burning and the positive movement of the ash can be varied, it will therefore be seen that I have provided a construction which enables a progressive feed stoker to be made in any required lengths and at the same time obtain the beneficial results required.

75 The lower part of the overfeed grate section has a combined movement, i. e., the grate members move both bodily in the direction of fuel feed to provide for the positive and continuous movement of the fuel bed and also move angularly about axes extending transversely of the fuel feed so as to agitate the fuel feed and thereby provide for the breaking down of the lanes at the proper point. Such agitation also provides for the breaking up of any clinker formation. The overfeed grate also provides for the positive admission of air to the fuel bed so as to effectively burn out the remaining combustible prior to its reaching the ash disposal apparatus.

80 As the degree of angular movement imparted to one portion of the overfeed grate section may be varied with respect to the degree of such motion imparted to another portion of the overfeed grate section, it will be readily seen that I have provided an overfeed grate section which is extremely flexible in operation, and by reason of this fact coals of varying characteristics may be effectively and efficiently burned.

85 It will be observed that in the accompanying drawings I have shown the underfeed section, the overfeed section, and the straight reciprocatory portion of the overfeed section as being of certain relative lengths. It is to be understood, however, that the showing is merely for the purposes of illustration and that the respective lengths of these portions of the progressive feed stoker shown may be varied at will without departing from the scope of the present invention.

90 While I have shown my invention in but one form, it will be obvious to those skilled

in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. In combustion apparatus, the combination with an underfeed stoker section comprising alternately-arranged retorts and tuyère rows, and means for feeding fuel to one end of the underfeed section; of an overfeed section disposed to receive the burning material from the other end of the underfeed section and comprising a series of grate members pivotally connected together in end-to-end relation and extending in the direction of fuel feed; means for supporting the first grate member considered in the direction of fuel feed for reciprocatory movement bodily in the direction of such feed; and means for imparting a combined oscillatory and reciprocatory motion to some of the remaining grate members of the series.

2. In combustion apparatus, the combination with an underfeed stoker section comprising alternately-arranged retorts and tuyère rows, and means for feeding fuel to one end of the underfeed section; of an overfeed section disposed to receive the burning material from the other end of the underfeed section and comprising a series of grate members pivotally connected together in end-to-end relation and extending in the direction of fuel feed; and means providing for reciprocatory movement of all of the grate members forming the series bodily in the direction of fuel feed and including means providing for the oscillation of at least one of the grate members of the series about axes extending transversely of the direction of fuel feed.

3. In combustion apparatus, the combination with a coking structure and means for feeding fuel to the coking structure; of an overfeed grate section disposed to receive the burning fuel from the coking structure and comprising a series of grate members pivotally connected together in end-to-end relation and extending in the direction of fuel feed; means for supporting the first grate member considered in the direction of fuel feed for straight reciprocatory motion only in the direction of such feed; and means for imparting an angular motion about axes extending transversely of the fuel feed, to at least one of the remaining grate members of the series.

4. In combustion apparatus, the combination with an underfeed stoker section comprising alternately arranged retorts and tuyère rows and means for feeding fuel to one end of the underfeed section; of an overfeed grate section disposed to receive the burning fuel from the underfeed section and

comprising a series of grate members pivotally connected together in end-to-end relation and extending in the direction of fuel feed; means for supporting the first grate member considered in the direction of fuel feed, for straight reciprocatory motion only in the direction of such feed; and means for imparting an angular motion about axes extending transversely of the fuel feed, to at least one of the remaining grate members of the series.

5. In combustion apparatus, the combination with a coking structure and means for feeding fuel to the coking structure of an overfeed grate section disposed to receive the burning fuel from the coking structure and comprising a series of grate members pivotally connected together in end-to-end relation and extending in the direction of fuel feed; and means for imparting a combined oscillatory and reciprocatory motion to the series of grate members at at least two spaced points and including means for varying the degree of motion imparted at one of such points with respect to the degree of motion imparted at the other of such points.

6. In combustion apparatus, the combination with an underfeed stoker section comprising alternately arranged retorts and tuyère rows, and means for feeding fuel to one end of the underfeed section; of an overfeed grate section disposed to receive the burning material from the other end of the underfeed section and comprising a series of grate members pivotally connected together in end-to-end relation and extending in the direction of fuel feed; and means for imparting a combined oscillatory and reciprocatory motion to the series of grate members at at least two spaced points and including means for varying the degree of motion imparted at one of such points with respect to the degree of motion imparted at the other of such points.

In testimony whereof, I have hereunto subscribed my name this 12th day of Sept., 1929.

DONALD J. MOSSHART.
